[57] CLAIM

The ornamental design for a cosmetologist's rod belt, as shown.

DESCRIPTION

FIG. 1 is a front elevational view of a cosmetologist's rod belt showing my new design;

FIG. 2 is a bottom plan view;

FIG. 3 is a side elevational view, the opposite being a mirror image;

FIG. 4 is a top plan view;

FIG. 5 is a rear elevational view; and

FIG. 6 is a perspective view.

FIG. 1
